UNITED STATES PATENT OFFICE.

FRED A. C. SKINNER, OF ST. LOUIS, MISSOURI.

RADIATOR.

Application filed July 22, 1925. Serial No. 45,199.

Special objects of this invention are to provide a radiator for heating and drying purposes, of particularly compact design and high thermal efficiency, which will be practical from a manufacturing standpoint and made up of readily available materials.

These and other desirable objects are attained by certain novel features of construction and combinations, including in part an arrangement of radiator tubes between headers and a series of thin flat sheets of high thermal conductivity connecting said tubes in the space between the headers.

The foregoing and other novel features of the invention will all appear in the course of the following specification in connection with the drawing accompanying and forming part of the same.

In the drawing one of the practical commercial embodiments of the invention is illustrated, it being understood that the structure may be varied from such disclosure without departure from the broad spirit and scope of the invention as hereinafter defined and broadly claimed.

Figure 1 is a broken plan view of the radiator.

Figure 2 is a front elevation of the same.

Figure 3 is a broken perspective and part 30 sectional view of one of the continuous fin sheets illustrating the relation of the same to the tubes and deflectors.

Figure 4 is an enlarged broken cross sectional view of the radiator as on substantially the plane of line 4—4 of Figure 1.

In the form of the invention herein disclosed, upper and lower substantially horizontal headers 3, 4 are provided, connected by rows of vertical tubes 5, 6. These radiator tubes are of oblong cross section, being shown as substantially diamond shaped and arranged with their major axes in line with the direction of air flow through the radiator. Also, the tubes 6 of the rear row are staggered or offset with respect to the tubes 5 of the front row so as to form a series of zigzag or circuitous air passages.

At the front side of the radiator the inclined sides of adjoining tubes provide funnel shaped entrances 7 to the air-ways and at the rear side of the radiator, deflectors 8 are shown having angularly related sides entered in the spaces between the tubes of the back row to split the departing air streams and confine the same to the rearward

sides of the tubes. The tubes in the second row divide the air streams into two channels 9 which unite at 10 in the spaces immediately to the rear of the front row tubes and the diffusers again divide these united streams 60 into channels 11 of greater cross sectional area than channels 9. Similarly, where the channels 11 meet at the rear at 12, these junction points (12) are of greater cross sectional area than the single channels at 10, 65 the increase in size being such as to allow for a normal expansion of air for the rise in temperature occurring during such flow.

By sweeping the air in closely confined relation about all sides of the tubes, a rapid 70 and effective transfer of heat takes place and by opening the passages wider in the direction of flow, a more rapid circulation is secured and hence a greater volume of air is heated. The circulation through the 75 radiator may be either natural or forced, a circulation fan or the like being used to facilitate the flow, if that is found desirable.

Connecting the tubes are a series of thin sheets 13 of high thermic conductivity shown 80 as substantially horizontal and spaced in parallel relation. The spacing of these plates may vary with the size and capacity of the radiator and the purpose for which it is intended and such spacing may vary 85 as between the upper and lower portions of the radiator so as to obtain an even or an uneven distribution of the heat as conditions may require. An intimate contact is effected between the radiator tubes and connecting 90 fin sheets, assuring direct conduction from the tubes to the sheets.

A practical method of assembly is to punch the sheets and then force them over the assembled tubes under sufficient pressure 95 to assure metal to metal contact at all points. In addition, brazed or soldered joints may be made or the entire structure may be tinned, galvanized or otherwise treated to complete an intimate joinder between the 100 sheets and tubes and to assure permanency of such joints.

The connecting sheets stratify the air or other flow and confine the same in the tortuous channels and these channels sweep 105 the air past all sides of the tubes without checking the full and free passage.

The continuous connecting fins may be made of thin sheet copper or other good thermally conductive material and similarly 110

the tubes may be made of thin sheet copper, as indicated. The headers also may be made of thin sheet metal such as copper, resulting on the whole in a maximum of heat conductivity with a maximum possibility of free and unrestricted air flow therethrough. As a heat exchange device therefore, the invention is of high efficiency and of particularly compact design for the results attained. By a proper distribution and spacing of the fin sheets, a substantially uniform and equal radiation of heat may be obtained. The tube and sheet construction also enables the building of the radiator as a relatively shallow body through which the air may be passed substantially unrestricted.

The bracing of the tubes by the continuous fin sheets strengthens and braces the structure so that light gage metal may be used for both tubes and fin sheets, resulting in a structure which is light in weight, durable and strong and in which all radiation is locked together in a close compact unit.

25 What is claimed is:

1. A radiator comprising radiator tubes arranged in rows with the tubes in one row staggered in the spaces between the tubes of an adjoining row to provide zigzag air courses, sheets of high thermic conductivity engaged about and connecting the tubes of the adjoining rows and deflectors in line with the spaces between the tubes of the last row for confining the departing air currents in engagement with the rearward surfaces of the last tubes.

2. A radiator comprising a series of radiator tubes, substantially diamond shaped in cross section and disposed with their major axes in the direction of air flow to provide a series of funnel shaped entrance passages for the air and deflectors disposed in line with the spaces between the tubes having angularly related sides substantially parallel to the rearward sides of the tubes to thereby divide the air stream and direct the divided streams into contact with the rearward sides of the tubes.

3. A radiator comprising a series of radiator tubes, substantially diamond shaped in cross section and disposed with their major axes in the direction of air flow to provide a series of funnel shaped entrance passages for the air and deflectors disposed in line with the spaces between the tubes having angularly related sides substantially parallel to the rearward sides of the tubes to thereby divide the air streams and direct the divided streams into contact with the rearward sides of the tubes and thin sheets of high thermic conductivity surrounding and connecting the tubes.

4. A radiator comprising upper and lower headers, upright tubes connecting said headers, said tubes being arranged in rows

and being oblong in cross section with the major axes disposed in the direction of normal air flow through the radiator, the tubes of one row being staggered with respect to those of another row to provide circuitous air passages and thin sheets of high thermic conductivity arranged in superposed spaced relation connecting the tubes and disposed in intimate heat conducting engagement with the walls of the tubes, the air passages being of gradually increasing area in the direction of normal air flow and deflectors in line with the spaces between the tubes of the last row for spreading the departing air currents into intimate contact with the walls of said tubes.

5. In a device of the character disclosed, circulating tubes arranged in a row to break up a flow of air past the same into a series of streams, and deflectors at the rear of said tubes in line with the spaces between the tubes and having air confining walls substantially parallel with the rearward sides of the tubes to thereby confine the departing air streams in sweeping engagement with the rearward surfaces of said tubes.

6. In a device of the character disclosed, circulating tubes arranged in rows, one row behind the other and the tubes in the rear-most row positioned in line with the spaces between the tubes in the preceding row and deflectors in rear of said rearmost tubes having confining surfaces in line with the spaces between said tubes and extending forwardly in substantial parallelism with the rearward sides of said tubes to thereby confine departing air currents in sweeping engagement with the rearmost surfaces of said last tubes.

7. In a device of the character disclosed, radiator tubes arranged in adjoining rows, said tubes being diamond shaped in cross section and disposed with their major axes in line with the flow of air travel through the device, the tubes of one row being staggered with respect to those in an adjoining row and disposed in line with the spaces between such tubes with the flat sides of the tubes all in one row in parallelism with the opposing flat sides of the tubes in the adjoining row, thereby providing continuously zigzag passages about the tubes for breaking up air flow into alternately divergent and convergent streams and flat fin sheets of high thermic conductivity engaged about the tubes connecting them rigidly in the described relation and stratifying the air flow to and about the tubes.

8. A radiator comprising upper and lower headers, upright tubes connecting said headers, said tubes being arranged in rows and being oblong in cross section with the major axes disposed in the direction of normal air flow through the radiator, the tubes of one row being staggered with respect to

those of another row to provide circuitous in spaced superposed relation connecting air passages, said air passages being of the tubes and disposed in intimate contact- gradually increasing area in one direction of ing engagement with the walls of the tubes. ¹⁰ normal air flow to allow for gradual expansion of the air as it is heated in its confined In witness whereof, I have hereunto set passage through the radiator and thin fin my hand this 14th day of July, 1925.

FRED A. C. SKINNER.
